Specification for Design.

Patented Apr. 20, 1920.

Application filed November 17, 1919. Serial No. 338,777. Term of patent 14 years.

To all whom it may concern:

Be it known that I, CHARLES LINCOLN TROUT, a citizen of the United States of America, residing in the borough of Manhattan, city, county, and State of New York, have invented a new, original, and ornamental Design for Wedding-Rings, of which the following is a specification, reference being had to the accompanying drawing, forming a part thereof.

The figure is a side or edge view of a wedding ring showing my new design.

I claim—

The ornamental design for a wedding ring as shown.

In witness whereof, I have hereunto signed my name.

CHARLES LINCOLN TROUT.
